UNITED STATES PATENT OFFICE.

CHARLES E. NUTTING, OF HOPEDALE, MASSACHUSETTS, ASSIGNOR, BY MESNE ASSIGNMENTS, TO DRAPER CORPORATION, OF PORTLAND, MAINE, A CORPORATION OF MAINE.

WEFT-THREAD CATCHER FOR AUTOMATIC WEFT-REPLENISHING LOOMS.

1,233,695.

Specification of Letters Patent. Patented July 17, 1917.

Application filed June 24, 1912. Serial No. 705,451.

To all whom it may concern:

Be it known that I, CHARLES E. NUTTING, of Hopedale, in the county of Worcester and State of Massachusetts, have invented a 5 Weft-Thread Catcher for Automatic Weft-Replenishing Looms, of which the following is a specification.

In automatic weft-replenishing looms, wherein a nearly spent weft-carrier is 10 automatically ejected from the running shuttle prior to the exhaustion of the weft, it is important to entirely withdraw the trailing weft thread of the ejected nearly spent weft carrier from the eye of the shuttle before the shuttle with the fresh weft-carrier can carry the trailing end of the spent weft into the shed, the effect of which would be to weave a double strand of weft into the cloth, thus interfering with the 15 perfect character of the cloth. The object of the present invention is to prevent such occurrence by supplying a weft thread catcher which will catch the trailing thread of the outgoing nearly spent weft-carrier and 20 insure the complete withdrawal of the trailing thread from the eye of the shuttle. The present invention is illustrated in the accompanying drawings, in which—

Figure 1, is a front elevation of so much 25 of the replenishing side of a weft-replenishing loom as is necessary for an understanding of the present invention. Fig. 2, is a perspective view of the weft thread catcher. Fig. 3, is a vertical section through 30 the lay and shuttle box and spent weft-carrier-receiver. Fig. 4, is a perspective view of the preferred construction of weft thread catcher.

The present invention is particularly intended for use with a so-called "feeler" loom 35 that is to say, an automatic weft-replenishing loom wherein the approaching exhaustion of the running weft institutes the action of the weft-replenishing mechanism, so that 40 the nearly spent weft-carrier is ejected and a fresh weft-carrier substituted therefor, prior to the complete exhaustion of the weft. A feeler loom of this character is typically 45 illustrated in United States Letters Patent 50 of James H. Northrop, No. 600,016, March 1, 1898. The present drawings illustrate only enough of the parts of such a loom to enable the present invention to be understood. In the drawings, A, is the lay and

B, is the shuttle shown as occupying the 55 shuttle-box at the supply side of the loom, where the weft-replenishing mechanism is located. The automatic swinging trans- ferrer C, of this weft-replenishing mecha- nism is shown in the position which it occu- 60 pies just after it has inserted a fresh weft- carrier in the shuttle, thereby ejecting the nearly spent weft-carrier which is shown at D, in Fig. 3, at the bottom of the can or re- ceiver E, which receives the spent weft-car- 65 riers. As shown in Fig. 3, the lay is slotted at F, in the usual manner, beneath the shuttle box so as to permit the downward escape of the spent weft-carriers.

Figs. 1 and 3, of the drawings show the 70 trailing end T, of the nearly spent weft thread. Fig. 3, shows this thread extending from the discharged weft-carrier D, to the shuttle B, and Fig. 1, shows the trailing end F, extending through the eye G, of the 75 shuttle and thence toward the cloth. This condition is one which occurs in practice and it often occurs that the shuttle on its next flight with the fresh weft-carrier carries the 80 spent weft thread T, into the shed, thus 85 weaving a double strand of weft. It is the object of the present invention to catch the trailing end T, of the spent weft and to withdraw it from the eye of the shuttle before it can be carried by the shuttle into the shed. 90

To this end, the fixed stud S, on which the swinging transffer C, turns, is pro- 95 vided with a downwardly projecting arm H, at its outer end which carries the sta- tionary extended weft thread catcher I. 90 The weft thread catcher I, extends length- wise of the lay and parallel therewith, and it has a toothed thread-engaging surface consisting of a large number of rows of numerous sharp teeth, which are inclined at 95 their outer ends away from the middle of the loom. Preferably, this toothed thread catcher is composed of a strip of card cloth- 100 ing, such as is employed in carding engines. The thread catcher thus constituted com- 105 prises an extended area both vertically and laterally supplying numerous rows each containing numerous teeth. Accordingly, whichever way a thread extends with re- 105 spect to the thread catcher it has presented in its path numerous sharp teeth. This strip of card clothing constituting the thread catcher is fastened to the rear horizontal

arm J, of a stationary holder, located in front of the lay, which has a bent forwardly extending arm K, having a horizontal slot L, at its front end by means of 5 which it is adjustably bolted to the depending arm H, which is vertically slotted at M, to receive the retaining bolt N. Accordingly, the thread catcher holder can be adjusted both vertically and in and out so as 10 to occupy the proper position during the weft-replenishing action.

Fig. 3, shows the lay A, at front center, that is to say, when it is substantially all the way forward, and at the position which 15 it occupies when the transerrer C, has just performed its transferring action. At this time, the thread catcher is located within the discharge slot F, of the lay and close to the rear wall of said slot, so that the nearly 20 spent weft-carrier is discharged in front of the thread catcher, and the trailing weft end T, extends in front of the thread catcher, as illustrated in Fig. 3. As shown in Fig. 1, the thread catcher extends outwardly (to 25 the right) approximately to a position immediately beneath the thread eye G, of the shuttle, and the forwardly extending bent arm K, of the thread catcher holder is located sufficiently to the right so as not to 30 interfere with the downward discharge of the nearly spent weft-carrier. The roughened or toothed surface of the thread catcher extends a sufficient distance parallel with the travel of the shuttle so as to insure 35 catching hold of the trailing end of the spent weft before the shuttle on its first flight can carry the spent thread in to the shed. The nearly spent weft-carrier having 40 been discharged from the shuttle when the lay occupies the position shown in Fig. 3, the lay then moves backwardly (to the right, as shown in Fig. 3) thereby carrying the shuttle backwardly with it and, accordingly, drawing the trailing end T, of the 45 spent weft thread against the teeth of the thread catcher. Accordingly, the thread is caught by the thread catcher before the shuttle is picked. When the shuttle is picked, the trailing end of weft is held by 50 the thread catcher and is consequently pulled out of the eye of the shuttle and stripped therefrom so that it is not carried by the shuttle into the shed.

It sometimes happens that a spent weft- 55 carrier is not promptly ejected, so that it does not drop from the lay in season and it may occur that the weft-carrier gets caught

between the rear side of the thread catcher and the lay, with resulting damage to the thread catcher. Accordingly, it is desirable to make the forwardly extending arm K, of the thread catcher holder of thin yielding 60 spring metal, as shown in Fig. 4. As the entire holder J, K, is preferably made of a single strip of sheet metal, the strip J, is likewise thin and yielding. As shown in Fig. 4, the front end of the holder where the slot I, is located is reinforced by plates on either side so as to be securely held to the depending arm H. With such a yielding 65 holder no damage is done if a weft-carrier does get trapped between it and the lay.

The thread catcher can be used on a loom wherein the weft-carriers are changed in case the weft breaks or is completely exhausted, 70 since, should the replenishment occur when the weft breaks, the ejected partly-filled weft-carrier may have a trailing thread which is in danger of being carried into the 75 cloth.

I claim—

1. A loom for automatically replenishing the weft in the working shuttle having, in combination, a lay; weft replenishing mechanism; and a thread catcher beneath the shuttle box at the replenishing side of the loom having an extended area of numerous sharp teeth to catch the trailing thread of a discharged weft carrier, whereby, whichever way a thread extends with respect 80 thereto, the thread catcher presents numerous teeth in its path.

2. A loom for automatically replenishing the weft in the working shuttle having, in combination, weft replenishing mechanism; a lay having a slot in the bottom of the shuttle box at the replenishing side of the loom; a yielding thread catcher holder below the shuttle box at the replenishing side of the loom; and a thread catcher on said yielding holder having an extended area of numerous sharp teeth to catch the trailing thread of a weft carrier discharged through the said slotted bottom, whereby, whichever way a trailing thread extends, the 85 thread catcher presents numerous teeth in its path.

In witness whereof, I have hereunto signed my name in the presence of two subscribing witnesses.

CHARLES E. NUTTING.
